UNITED STATES PATENT OFFICE.

EDWARD L. TAFT, OF GARDNER, MASSACHUSETTS, ASSIGNOR OF ONE-HALF TO JAMES L. CHAPMAN, OF WORCESTER, MASSACHUSETTS.

WOOD-PLANING MACHINE FOR SHAPING WARPED OR IRREGULAR SURFACES.

SPECIFICATION forming part of Letters Patent No. 561,359, dated June 2, 1896.

Application filed December 20, 1893. Serial No. 494,195. (No model.)

To all whom it may concern:

Be it known that I, EDWARD L. TAFT, a citizen of the United States, residing at Gardner, in the county of Worcester and State of Massachusetts, have invented a new and useful Improvement in Wood-Molding Machines for Forming Warped or Irregular Surfaces, of which the following is a specification, accompanied by drawings forming a part of the same, and in which—

Figure 1 represents a top view of a machine embodying my invention. Fig. 2 is a side view of the same. Fig. 3 is an end view. Fig. 4 is a transverse view of the two carriages upon which are supported the work to be planed and the pattern by which the vertical movement of the cutter-head is determined, the section being shown upon a line 4 4, Fig. 1, having the same curvature 15 as the path of the cutter. Fig. 5 is a top view of the loose gear carrying the actuating-pawl, by which an intermittent motion is imparted to the feed-screws. Fig. 6 represents the under side of the same. Fig. 7 is a central sectional view of the same. Fig. 8 is a top view of the work-holding carriage, and Fig. 9 is a central sectional view of the same on line 9 9, Fig. 8. Fig. 10 is a rear view of the pattern-wheel and sliding plate, showing 20 its actuating-screw; and Fig. 11 is a sectional view of Fig. 10.

Similar letters refer to similar parts in the different figures.

The object of my present invention is to provide a wood-planing machine by which the surface of the work can be planed so as to present a warped or irregular surface corresponding with the surface of a determined pattern.

The machine embodying my present invention is capable of being used for a great variety of woodwork requiring an irregular or warped surface, and in the accompanying drawings I have represented such a machine as adapted to form the irregular or varying upper surface of a wood chair-seat; and my invention consists in providing a cutter-head capable of traversing across the surface to be cut and having a rising and falling motion 45 during its traversing movement across the work as determined by the shape of a set

pattern, and, further, in the construction and arrangement of the several parts by which this result is secured, as hereinafter described, and pointed out in the annexed 55 claims.

Referring to the accompanying drawings, A denotes the framework of the machine, by which the operating parts are supported.

A' A' denote an upper and lower pair of 60 horizontal rails supported by the framework and provided upon their inner sides with ways for two carriages or feed-tables B and B'. Upon the upper carriage B is attached the work to be planed, which in the accompanying drawings represents a wood plank 65 or block B² from which a chair-seat is to be formed. Upon the lower carriage B' is fastened an iron plate B³, having its upper surface shaped to correspond with the desired 70 form of the chair-seat. The carriages B and B' are provided upon their lower sides with lugs B⁴ and B⁵, each having a screw-thread 75 engaged by the rotating screws B⁶ and B⁷, causing a feeding motion to be simultaneously imparted to the carriages B and B', so as to carry the work forward beneath a revolving cutter-head and at the same time carry the pattern B³ forward beneath a pattern-wheel, which rolls over its surface. 80

The screws B⁶ and B⁷ are driven from a vertical shaft B⁸ through intermediate miter-gears B⁹ B¹⁰ and B¹¹ B¹². The vertical shaft B⁸ has attached thereto a ratchet B¹³, which is engaged by a pawl B¹⁴, carried by the gear-wheel B¹⁵, which turns loosely upon the vertical shaft B⁸ and receives an intermittent motion by means of a sliding rack B¹⁶, connected by a link B¹⁷, Fig. 1, with a crank-plate B¹⁸ on a vertical shaft B¹⁹. The vertical shaft B¹⁹ is driven by miter-gears B²⁰ and B²¹ from the horizontal driving-shaft B²², which receives its motion through a belt-pulley B²³ and clutching mechanism B²⁴. 85 90

Projecting from the frame are arms C C', 95 each arm holding a stud C² C², upon which is pivoted a circular frame C³. Pivoted upon a horizontal axis within the circular frame C³ is a cross-bar C⁴, from one end of which extends a framework C⁵, consisting of a web C⁶ 100 and stiffening-ribs C⁷ C⁷. The opposite end of the frame C⁵ is attached by bolts C⁸ to a

yoke C⁹, elliptical in form and connected at one end by a link C¹⁰ with a vibrating lever C¹¹, which turns upon a stud C¹² and is provided with a slot C¹³, in which slides a block 5 C¹⁴, pivoted upon a stud C¹⁵. The stud C¹⁵ is attached to a rotating crank-arm C¹⁶, which is provided with a slot C¹⁷, in order to allow a radial adjustment of the stud C¹⁵ for the purpose of varying the angular movement of 10 the vibrating lever C¹¹. By the rotation of the crank-arm C¹⁶ and the angular motion of the lever C¹¹ the yoke C⁹ is swung back and forth upon the studs C² C². Upon the under side of the framework C⁵ are placed two journal-bearings C¹⁸ C¹⁸ to hold a revolving shaft C¹⁹, which is provided at one end with a belt-pulley C²⁰ and at the other end with a revolving cutter-head C²¹, which is carried back and forth over the surface of the chair-seat by the 15 traversing movement of the yoke C⁹. The lower portion of the yoke C⁹ carries a pattern-wheel C²², having its diameter corresponding to the diameter of the cutter-head C²¹ and turning upon a stud C²³, which is carried 20 upon a plate C²⁴, sliding in ways formed in the yoke and actuated by a screw C²⁵, so that the vertical position of the pattern-wheel C²² in the yoke C⁹ can be slightly varied. 25

The crank-arm C¹⁶ is carried upon the upper 30 end of a vertical shaft D, driven from the horizontal driving-shaft B²² through the miter-gears D' and D². The reverse movement of the carriages B and B' is accomplished by a horizontal shaft E, journaled in bearings 35 supported by the framework and driven by means of the belt-pulley E' and clutching mechanism E². Upon the end of the horizontal shaft E is a bevel-gear E³, engaging the bevel-gear E⁴ upon the vertical-shaft B⁸, the 40 motion of the horizontal shaft E serving to reverse the motion of the feed-screws B⁶ and B⁷ and produce a quick return of the carriages B and B' by disengaging the pawls B¹⁴ from the ratchet B¹³. The clutching devices 45 E² and B²⁴ are operated by means of the hand-levers F and F'.

The pattern B³ consists of an iron plate which is attached to the lower carriage B', the upper surface of the plate corresponding to 50 the shape of the surface to be formed upon the plank or block B². The plank or block B² is attached to the upper carriage B by means of pins G, adapted to enter holes G' in the under side of the block B² and carried by 55 the plates G², sliding in ways formed in the upper surface of the carriage B. The plates G² are connected by links G³ with crank-pins G⁴, held in a rotating disk G⁵, which is attached to a spindle G⁶, journaled in the carriage B² and carrying on its lower end a worm-gear G⁷, which is engaged by a worm G⁸ on a shaft G⁹, journaled in bearings G¹⁰ upon the under side of the carriage B and having a hand-wheel G¹¹ by which the shaft is turned 60 to rotate the disk G⁵. The sliding plates G² are moved out and the block B² is applied to the carriage with the pins G entering the 65

holes G', when the disk G⁵ is rotated, drawing the plates in toward the center far enough to cause the pins G to bind against the side of 70 the holes G' and hold the block B² from movement on the surface of the carriage B.

The driving-pulley C²⁰ is located at the intersection of the vertical and horizontal axes of the frame C⁵, so that the action of the belt 75 by which the pulley C²⁰ is driven will not be materially affected by the angular motion of the frame C⁵ in either a horizontal or a vertical plane. The angular movement of the frame C⁵ in a vertical plane, or about the horizontal axis of the cross-bar C⁴, is slight and is due to the irregularity in the surface of the plate B³, over which the pattern-wheel rolls. The angular motion of the frame C⁵ in a horizontal plane, or about the vertical axis of the 80 stud C² C², is greater in extent; but it produces only a slight twist in the belt as the yoke C⁹ approaches each end of its traversing motion.

The screw C²⁵, by which the pattern-wheel 90 C²² is raised and lowered within the yoke, is journaled in an arm C²⁶, projecting from the side of the yoke, the screw entering a screw-threaded lug C²⁷ upon the side of the sliding plate C²⁴, which carries the stud C²³, upon 95 which the pattern-wheel C²² rotates. This vertical adjustment of the pattern-wheel upon the yoke C⁹ allows the cutter-head C²¹ to be raised or lowered, with reference to the surface of the upper carriage B, in order to determine the thickness of the completed chair-seat.

The pawl B¹⁴ is preferably attached to a spindle H, journaled in the gear-wheel B¹⁵, and having upon its upper end a handle H' 105 to allow the pawl to be conveniently disengaged from the ratchet B¹³. A spring H² acts upon the pawl B¹⁴ in the usual manner.

The operation of the machine is as follows: 110 The block B² to be cut is attached to the upper carriage B, in the manner described, with its surface to be acted upon directly over the corresponding surface of the pattern-plate B³. The rotating pulley B²³ is connected with the horizontal driving-shaft B²² by means of the 115 clutching mechanism B²⁴, causing the rotation of the vertical shaft D and crank-arm C¹⁶, thereby vibrating the lever C¹¹ and by means of the link C¹⁰ imparting an angular motion to the frame C⁵ and yoke C⁹ and causing the 120 rapidly-revolving cutter-head C²¹ to be traversed back and forth over the face of the blocks B² in a circular path concentric with the studs C² C². As the yoke C⁹ is traversed back and forth the pattern-wheel C²² will roll 125 over the pattern-surface of the iron plate B³, carried upon the lower carriage B', the pattern-wheel, following any irregularities in the surface of the pattern-plate, causing the yoke C⁹ to rise and fall, as determined by the character of the surface over which the pattern-wheel C²² rolls, the yoke C⁹ being capable of a rising-and-falling motion by means of the 130 horizontally-pivotal connection of the cross-

bar C⁴ within the circular frame C³. As the revolving cutter C²¹ is carried in a circular arc across the surface of the block B² it will cut a path varying in depth, as determined by the contour of the pattern-plate B³, and as the cutting operation proceeds the block B² and pattern-plate B³ are simultaneously moved along by the feeding motion of the tables B and B', caused by the intermittent rotation of the screws B⁶ and B⁷, as already described, so that when the block B² has entirely passed beneath the action of the cutter-head C²¹ the upper surface of the block will exactly correspond with the upper surface of the pattern-plate B³. The driving-pulley B²³ is then disconnected from the shaft B²² and the pawl B¹⁴ thrown out of engagement with its ratchet, allowing the carriages to be reversed by connecting the rotating pulley E' with the shaft E.

I do not confine myself, so far as the first part of my invention is concerned, to the specific construction and arrangement of parts as herein described and represented in the accompanying drawings, as it is obvious that changes can be made which would not depart from the scope of my invention. For example, the two carriages B and B' might be arranged to move upon the same track, one carriage following the other, or the carriages might be arranged to move upon separate tracks lying in the same horizontal plane, and the cutter-head and pattern-wheel might be carried in separate frames operatively connected together, so that the movement of the pattern-wheel frame would be simultaneously imparted to the cutter-head frame and the method of so connecting the pattern-wheel frame and the cutter-head frame would come within the province of a mechanic skilled in the construction of woodworking machinery. Neither do I confine myself to the use of a frame for carrying a cutter-head or pattern-wheel and capable of an angular movement in both a vertical and horizontal plane, as it will be obvious that in lieu of a carrying-frame pivoted at one end and capable of an angular movement, such as I have shown and described, a carrying-frame for the cutter-head could be employed having a rising and falling motion in vertical ways, the entire traversing motion imparted to the cutter-head being transferred to the carriages themselves.

The gist of my invention consists in providing and combining in a machine of the character described, first, means for holding the work against the action of a revolving cutter-head; second, a revolving cutter-head, said cutter-head being capable of a traversing and feeding motion relatively to the surface of the work by means of a movement imparted either to the cutter-head, to the work, or to both; third, a pattern-plate provided with a surface corresponding to the contour which it is desired to form upon the work by the action of the cutter, and, fourth, a pattern-

wheel rolling in contact with the pattern-surface and operatively connected with the cutter-head, so that the movement of the pattern-wheel, as controlled by the pattern-surface, will be simultaneously imparted to the cutter-head.

I am aware that lathes for turning irregular forms have long been in use, in which the movement of a revolving cutter-head is controlled by the movement of a pattern-wheel rolling in contact with the pattern-surface; but in machines of this class the work is rotated against the pattern-wheel and the machine is incapable of forming an irregular surface by a traversing motion of the cutter-head over the plane surface, and a machine capable of shaping a warped or irregular surface upon the plane surface of the work in the manner I have already described I deem to be, broadly, new.

What I claim as my invention, and desire to secure by Letters Patent, is—

1. A wood-molding machine having a vibrating frame by which a cutter-head is traversed over the surface to be operated upon, a cutter-head carried upon a rotating shaft, a rotating shaft journaled on said frame and carrying said cutter-head, said shaft having its axis at right angles with the line of motion of said cutter-head as it is carried by said vibrating frame, whereby the cutting edge of said cutter-head is advanced against the wood by the movement of said frame, means for raising and lowering said cutter-head during the vibration of said frame, and means for feeding the work transversely to the line of motion of said cutter-head as it is carried by said frame, substantially as described.

2. The combination of carriages B and B', a clamping mechanism by which the work can be attached to one of said carriages, a pattern-plate attached to the other of said carriages, connected means by which a feeding motion is imparted to said carriages, a frame capable of an angular motion in both a horizontal plane and a vertical plane, a shaft journaled in bearings on said frame and carrying a belt-pulley and a cutter-head, a pattern-roll, or pattern-wheel carried by said frame, and in contact with said pattern-plate, connected means by which an angular motion is imparted to said frame in a horizontal plane, whereby the cutter-head is traversed over said work-holding carriage, said frame being capable of an angular movement in a vertical plane, as moved by the irregularity in the surface of the pattern-plate, substantially as described.

3. The combination of carriages B and B', connected means for imparting a feeding motion to said carriages, a yoke C⁹ having an attached frame C⁵, pivoted within a circular frame C⁴, a circular frame C⁴ pivoted upon studs C², C², held by the fixed framework of the machine, a cutter-head carried by said frame C⁵, a roll or pattern-wheel carried by

said yoke, a pattern-plate attached to one of said carriages and in contact with said pattern-wheel and means whereby said frame C⁵ and connected yoke are oscillated upon their studs C², C³, and said pattern-wheel rolled over the surface of said pattern-plate, causing a rising-and-falling motion to said cutter-head, corresponding to the irregularities of said pattern-plate, substantially as described.

4. The combination of carriages B and B', provided with screw-threaded lugs B⁴ and B⁵, feed-screws B⁶ and B⁷ connected by gears with a shaft B⁸, shaft B⁹, gear B¹⁵ turning loosely on said shaft, a pawl carried by said gear, a ratchet attached to said shaft and engaged by said pawl, a reciprocating rack engaging said gear, whereby an intermittent feeding motion is imparted to said carriages and a cutter-head revolving above the surface of one of said carriages, a pattern-plate attached to the other of said carriages, and a roll, or pattern-wheel, arranged to roll on the surface of said pattern-plate, said pattern-wheel being connected with said cutter-head, so as to raise and lower the same in corre-

spondence with said pattern-plate, substantially as described.

5. The combination of the carriages B and B', connected feeding mechanism, pivoted frame adapted to move in both a horizontal and vertical plane, a cutter-shaft journaled on said pivoted frame, a cutter-head held on said shaft, a roll or pattern-wheel carried by said frame, a vibrating lever connected with said pivoted lever and a crank-arm actuating said lever, substantially as described.

6. The combination of the carriages B and B', pivoted frame adapted to move both in a horizontal and vertical plane, a cutter-head carried by said frame, a roll or pattern-wheel carried by said frame, a pattern-plate having its surface in contact with said roll, or pattern-wheel, crank-arm and intermediate mechanism between said crank-arm and said pivoted frame, substantially as described.

Dated this 13th day of December, 1893.

EDWARD L. TAFT.
